UNITED STATES PATENT OFFICE.

GEORGE H. CROSS, OF ST. JOHNSBURY, VERMONT.

DESIGN FOR A CORN-CAKE.

SPECIFICATION forming part of Design No. 29,882, dated December 27, 1898.

Application filed November 12, 1898. Serial No. 696,303. Term of patent 14 years.

To all whom it may concern:

Be it known that I, GEORGE H. CROSS, a citizen of the United States, residing at St. Johnsbury, in the county of Caledonia and State of Vermont, have invented and produced a new and original Design for a Corn-Cake, of which the following is a specification, reference being had to the accompanying drawings, forming a part thereof, in which—

My invention consists in the design forming the subject-matter of the accompanying illustration, in which the cake is presented with a flat base A, the flat ends B, perpendicular to the base A, and the curved upper surface C, curving on the arc of a circle from one edge to the opposite edge of the base A, 20 and connecting the curved upper edges of the plane ends B, as best shown in Fig. 1, the specific cross-sectional form of the cake being best shown by the end view, Fig. 2.

Having described my invention, what I 25 claim as new, and desire to secure by Letters Patent, is—

The design for a corn-cake, as herein shown and described.

GEORGE H. CROSS.
